COPYING PROCESS

Ernst Schätzler, Basel, Switzerland, assignor to
 Porros Patentverwaltung A.-G. Basel, Basel,
 Switzerland

Application May 11, 1932, Serial No. 610,713
 In Germany May 18, 1931

2 Claims. (Cl. 41—31.5)

According to the known copying processes the copying sheets are moistened before being pressed so that during the pressing the moisture of the copying sheet in question dissolves a portion of 5 the ink from the original. This dissolved ink of the original is at the same time transferred to the copying sheet during the pressing.

The duplicating process according to the invention differs fundamentally from these known processes in that the copying sheets are not moistened but the original bearing reversed script capable of transfer is moistened on the side remote from the script or picture, and that dry copying sheets are successively pressed against 10 the front side bearing the original reversed script in a separate operation.

Spirit, alcohol, water or any other solvent for the ink may be employed for moistening the rear side of the original, that is the side remote from 15 that bearing the script or picture. Spirit and alcohol are to be used if up to sixty copies are to be made, but organic solvents for several hundreds of copies.

Any kind of writing paper may be employed 20 for the original and any copying ink, such as crystal violet, may be used for producing the mirror reflected script.

The solvent is applied to the original by moistening the rear side thereof.

25 This may be effected directly. However, suitable apparatuses can be advantageously employed for moistening the original and producing the duplicates.

Such apparatus are illustrated by way of example in the accompanying drawing in which:—

Fig. 1 is a perspective view of a flat duplicator.

Fig. 2 shows a rotary duplicator in section.

The flat duplicator according to Fig. 1 consists of a plane plate *c* with an absorbent upper surface *b*. The solvent is applied to this absorbent surface for example by means of a brush or the like, whereupon the sheet *a*, bearing the original in mirror reflected script, is placed on the moistened surface with its side bearing the original script directed uppermost and pressed for example by means of a roller. By the pressure the moisture of the surface *b* is transferred to the original and moistens it uniformly on its rear side. The dry copying sheets are then placed 40 successively on the dry upwardly directed side of the original sheet and pressed for example by rolling a roller thereover. Thus the ink of the original which is continually being dissolved by the moisture percolating through the paper sheet is transferred to the copying sheets.

The drum *g* of the rotary duplicator illustrated in Fig. 2 likewise has an absorbent surface *d*, for example a cotton covering, which can be moistened with a brush or the like. The sheet *e* bearing the original in mirror reflected script or picture is clamped on the moistened drum surface *d* in known manner, for example by means of a clamping device *f* with its front side bearing the script directed outwards. Owing to the pressure between the drum *g* and the counter pressure roller *h* the solvent is transferred from the absorbent drum surface *d* to the rear side of the original sheet *e* and moistens the same. The dry copying sheets *i* are then passed between the drum *g* and counter pressure roller *h* and 15 pressed against the dry front side of the original as is customary in other processes, the ink being gradually dissolved by the moisture percolating through the sheet and transferred to the copying sheets.

20 The original is only slightly moistened. As the copy sheets are pressed on to the original by light rolling, no appreciable quantity of moisture will be absorbed from the original. If the original is moistened once with alcohol or spirit about 25 60 copies can be obtained. As the moistened surface is protected by the sheet of the original, the solvent will not evaporate too quickly. If several hundreds of copies are to be made organic solvents are to be used.

25 The new copying process results in a saving in time and material and in other advantages. It is only necessary to moisten the original once for all copies. According to the known process each individual copying sheet had to be moistened 30 which required much more time. The working with the new process is much quicker because the ink of the original continually dissolves and is ready for transferring after a single moistening. Hitherto the working speed was limited in 40 that the moisture of the copying sheet had to first dissolve the ink of the original. Moreover, according to the new process the drying of the copying sheets after the pressing is saved.

45 The saving in material is considerable, as the single moistening of the original requires much less solvent than the moistening of all the copying sheets.

In duplicating apparatuses operating according to the known process with a bar for moistening the copying sheets, that portion of the copying sheets which is enclosed between the moistening bar and the drum is lost. Moreover, it was impossible to print copies of very small size. As 50 in apparatus according to the new process the 55

moistening of the copying sheets is done away with, the head bar is utilized to full advantage and the printing of papers of very small size is possible.

5 Hitherto the strength of the copying sheet was detrimentally affected by the moistening. As according to the new process the copying paper remains dry, it is capable of resisting mechanical stresses to a greater extent. Consequently, 10 thinner and also perforated paper can be employed for the copies. Moreover, moist paper has a tendency to roll and crease. These objections are also overcome according to the invention in that the copying sheets remain dry.

15 I claim:—

1. A duplicating process, consisting in produc-

ing an original in mirror reflected script or picture in copying ink on a sheet of paper, moistening this paper on the rear side, and in successively pressing the dry copying sheets on to the front side of the original bearing the mirror reflected script or picture.

2. A duplicating process consisting in producing an original in mirror reflected picture or script in copying ink on a sheet of paper, moistening this paper on the rear side with a solvent 10 for the copying ink, thereby making the original ready for copying, and in successively pressing dry copying sheets on to the front side of the original bearing the mirror reflected picture or script.
